STORAGE BATTERY TERMINAL POST

Charles E. Hoover, Lancaster, Pa.

Application November 17, 1933, Serial No. 698,518

2 Claims. (Cl. 173—259)

The present invention which relates to storage batteries has particular reference to the construction of the battery posts to which the circuit wires are connected.

5 The object of my present invention is to provide a battery terminal post of a flat type and to provide an adapter for cooperation therewith when the battery is to be used as a replacement for one having the ordinary round post which 10 takes a split cable terminal clamp.

Other objects will in part be obvious and in part be pointed out hereinafter.

To the attainment of the aforesaid objects and ends the invention still further resides in the 15 novel details of construction, combination and arrangement of parts, all of which will be first fully described in the following detailed description and then be particularly pointed out in the appended claims, reference being had to the accompanying drawing, in which:—

Figure 1 is a detail plan view of a portion of a battery with a flat type terminal post and my invention applied thereto.

Figure 2 is a detail section on line 2—2 of 25 Figure 1.

In the drawing 1 represents the battery and 6 the base flange of the post. The post has a threaded portion 11 to receive the nut 15 by which it is secured to the top of the battery. Over the 30 threaded portion is the flat post head 12 which has a bolt hole 13. The top of the threaded portion 11 is flat adjacent the head 12. The adapter comprises a base portion 22 having a flat end to engage the post head 12 and a flat portion 28 to engage the top of the threaded portion 11. The base is bored to receive the bolt 26 having the nut 27 and the head 25, the latter being held in a recess 24 so as to prevent the turning of the bolt. Projecting from the base 22 is the usual round 35 post end 23 of a form to receive the connector of the ordinary split loop clamp on the wire or cable

to be attached to the battery. It will thus be seen that a service station need be equipped only with the battery posts, U-shaped cable terminals and the adapters in order to have a full complement of spare parts and in order to enable the same to service both the batteries with the old style posts and those with my new invention.

5 From the foregoing description, taken in connection with the accompanying drawing, it is thought that the construction, operation and advantages of my invention will be clear to those skilled in the art to which it appertains.

10 What I claim is:

1. A battery post having an upstanding portion of substantially rectangular horizontal section to 15 provide two parallel faces, said upstanding portion having a cross bolt-hole, said post having a horizontal seat surface adjacent the rectangular portion, in combination with an adapter comprising a base to engage one flat face of said post 20 and to engage said seat, said base having a bolt hole, a bolt passed through said bolt hole with a nut to clamp said adapter to said post, said adapter including a circular post extending from the base to receive a loop split clamp. 25

2. A battery post having an upstanding portion of substantially rectangular horizontal section to provide two parallel faces, said upstanding portion having a cross bolt-hole, said post having a horizontal seat surface adjacent the rectangular 30 portion, in combination with an adapter comprising a base to engage one flat face of said post and to engage said seat, said base having a bolt hole, a bolt passed through said bolt hole with a nut to clamp said adapter to said post, said 35 adapter including a circular post extending from the base to receive a loop split clamp, said base having a bolt head receiving and fitting socket to hold the bolt against turning.

40 CHARLES E. HOOVER.
